[57] CLAIM

The ornamental design for a microdissectomy curette
handle, as shown and described.

DESCRIPTION

FIG. 1 is a right side perspective view of a microdissectomy
curette handle, showing my new design;

FIG. 2 is a right side elevational view thereof, the left
side elevational view being a mirror image;

FIG. 3 is a top plan view thereof;

FIG. 4 is a bottom plan view thereof;

FIG. 5 is a left end elevational view thereof;

FIG. 6 is a right end elevational view thereof;

FIG. 7 is a right side perspective view of a second
embodiment of FIG. 1;

FIG. 8 is a right side elevational view thereof, the left
side elevational view being a mirror image;

FIG. 9 is a top plan view thereof;

FIG. 10 is a bottom plan view thereof;

FIG. 11 is a left end elevational view thereof; and

FIG. 12 is a right end elevational view thereof.

The broken line showing in FIGS. 1-4 and 7-9 is for
illustrative purposes only and forms no part of the
claimed design.
